[57] CLAIM

The ornamental design for a freon recovery and purification unit, as shown and described.

DESCRIPTION

FIG. 1 is a front elevational view of a freon recovery and purification unit showing my new design;

FIG. 2 is a right side elevational view thereof, the opposite side being identical in appearance;

FIG. 3 is a top plan view thereof;

FIG. 4 is a rear elevational view thereof; and

FIG. 5 is a bottom plan view thereof.
